UNITED STATES PATENT OFFICE.

LAFAYETTE KINZEL, OF CINCINNATI, OHIO.

COMBINED CLAMP-HANDLE AND WRENCH FOR HOSE.

SPECIFICATION forming part of Letters Patent No. 283,714, dated August 21, 1883.

Application filed June 18, 1883. (No model.)

To all whom it may concern:

Be it known that I, LAFAYETTE KINZEL, a citizen of the United States, and a resident of Cincinnati, in the county of Hamilton and State of Ohio, have invented certain new and useful Improvements in Combined Clamp-Handle and Wrench for Hose, of which the following is a specification.

My invention relates to a combined hose wrench and clamp.

The object of my invention is to provide a suitable tool for grasping and handling sections of fire-hose, and which will also serve as a wrench to uncouple two or more sections of hose. It is difficult to handle hose used with fire-engines when the same are under pressure of the pumping agency, and to carry the same up and down ladders and move them from place to place to accommodate the firemen.

My device is adapted to be used with one hand. My device grasps the hose readily and holds it, so that it will not slip upon the hose, allowing the use of it in going up and down ladders and other places where it is difficult to employ both hands. My invention accomplishes this object more perfectly than devices hitherto employed. At the same time it is adapted to be used as a wrench for uncoupling the joints without any change of the parts, so that the clamp and wrench or spanner are one and the same device, and adapted at all times to either use, as occasion may require. At the same time its construction is such that the operator, when using it as a clamp, can handle the hose with convenience.

Figure 1 represents my improvement shown in relation to a section of hose and opened to span the same. Fig. 2 shows my improvement clamped round a section of hose. Fig. 3 is an elevation of my device secured to the coupling as a wrench. Fig. 4 is a section on line x x , Fig. 3.

A represents a section of ordinary hose.
B represents a hose-coupling.

C C represent studs or spurs cast on and with coupling B in the ordinary manner, to enable the wrench to be employed for turning the coupling.

D E represent circular jaws or tongs of a size and curvature to clasp or encircle the hose.

F G represent shanks of the tongs, the limbs of which are united together by a rivet, a.

b c represent links welded in the eye of shanks F G.

H indicates a handle, composed of a bar having eyes at its ends for receiving the links b c, whereby the handle is connected with the shanks F G. The bar may be covered with leather, rubber, or other yielding material, to serve as a pad for the hand.

d represents holes pierced in the jaws D E, opposite each other, and adapted to engage over the studs C, as shown in Figs. 3 and 4, when the device is used as a wrench to uncouple sections of hose. When used as a clamp, the operator grasps the handle H and lifts or pulls upwardly, canting the jaws D E over and causing the front and rear edges of the jaws to compress the hose slightly and prevent the slipping of the tool upon the hose, and gives the operator great leverage of power to exert his strength upon the flexible handle H, enabling him to much more easily and conveniently move the hose. In letting go to obtain a new hold he simply slackens his hold, releases the jaws slightly, slips the tool back, and pulls on the handle H, as before described, all of which can be readily performed with one hand alone.

By reversely curving the shanks F G a short compact tool is provided, which can be readily carried in the pocket, the links b c permitting the handle to be folded down for portability.

What I claim as my invention, and desire to secure by Letters Patent, is—

1. A hose clamp and wrench composed of the circular jaws D and E, pivoted together, and each having a perforation, d, and a shank 90 provided with a link, and a handle having eyes at its ends, connected with the links, substantially as described.

2. The hose-clamp consisting, essentially, of the circular jaws D E, pivoted together by rivet a, and having the reversely-curved shanks F G, connected by the handle H, hinged thereto, substantially as herein set forth.

In testimony whereof I have hereunto set my hand.

LAFAYETTE KINZEL.
